(57) **CLAIM**

The ornamental design for clutch bag as shown and described.

DESCRIPTION

1. Clutch bag

2. Clutch bag

3. Clutch bag

1.1 : Front-side perspective view

1.2 : Right side view

1.3 : Left side view

1.4 : Front

1.5 : Rear view

1.6 : Top

1.7 : Bottom

1.8 : Rear-top perspective view in a first configuration of use

1.9 : Rear-top perspective view in a second configuration of use

2.1 : Front-side perspective view

2.2 : Right side view

2.3 : Left side view

2.4 : Front

2.5 : Rear view

2.6 : Top

2.7 : Bottom

2.8 : Rear-top perspective view

3.1 : Front-side perspective view

3.2 : Right side view

3.3 : Left side view

3.4 : Front

3.5 : Rear view

3.6 : Top

3.7 : Bottom

Fig. 1.1 is a front-side perspective view, Fig. 1.2 is a right

side view, Fig. 1.3 is a left side view, Fig. 1.4 is a front view,

Fig. 1.5 is a rear view, Fig. 1.6 is a top view, Fig. 1.7 is a

bottom view, Fig. 1.8 is a rear-top perspective view in a first

configuration of use, Fig. 1.9 is a rear-top perspective view

in a second configuration of use; Fig. 2.1 is a front-side

perspective view, Fig. 2.2 is a right side view, Fig. 2.3 is a

(Continued)

left side view, Fig. 2.4 is a front view, Fig. 2.5 is a rear view, Fig. 2.6 is a top view, Fig. 2.7 is a bottom view, Fig. 2.8 is a rear-top perspective view; Fig. 3.1 is a front-side perspective view, Fig. 3.2 is a right side view, Fig. 3.3 is a left side view, Fig. 3.4 is a front view, Fig. 3.5 is a rear view, Fig. 3.6 is a top view, Fig. 3.7 is a bottom view; the broken lines shown in design 1 are for the purpose of illustrating portions of the clutch bag and forms no part of the claimed design; minor colour variations in designs 2 and 3 are due to different lighting conditions.

1 Claim, 24 Drawing Sheets
